UNITED STATES PATENT OFFICE.

WALTER L. CULVER, OF ST. LOUIS, MISSOURI, ASSIGNOR TO THE WROUGHT IRON RANGE COMPANY, OF SAME PLACE.

DESIGN FOR A WATER-BACK FOR RANGES OR STOVES.

SPECIFICATION forming part of Design No. 32,293, dated February 27, 1900.

Application filed February 5, 1900. Serial No. 4,151. Term of patent 14 years.

To all whom it may concern:

Be it known that I, WALTER L. CULVER, of the city of St. Louis, State of Missouri, have invented and produced a new and original 5 Design for a Water-Back for Ranges or Stoves, of which the following is a full, clear, and exact description, reference being had to the accompanying drawings, forming a part hereof.

10 In the drawings, Figure 1 is a view in perspective showing my complete design. Fig. 2 is a vertical cross-section of the same.

My design consists of the vertical base or fire plate 1, integral with which are the horizontal top 2, the vertical sides 3, and the 15 short horizontal bottom 4. The said short bottom is extended into the inclined bottom 5. The sides 3 and the inclined bottom 5 converge at their ends, forming the flat annular surface 6.

20 A flange 7 is integral with the top 2, in vertical alinement with the surface 6, and is rounded, so that the said surface is a complete circle, through the center of which is an aperture 8, the upper side of 25 which is in alinement with the inner side of

the top 2, Fig. 2. A tubular projection 9 is integral with the said annular surface 6, around the aperture 8, and is provided throughout its length with the exterior threads 10. A flange 11 is integral with each 30 of the sides 3 in alinement with the forward edge of the short bottom 4, and a flange 12, in alinement with the flanges 11, is provided integral with the horizontal top 2. At the upper edge of the base 1 is a forwardly-projecting integral portion 13, the forward edge of which is in vertical alinement with the flanges 11 12 and integral with the center of which is an upwardly-projecting apertured ear 14. 35

I claim—

The design for a water-back for ranges and stoves, substantially as herein shown and described.

In testimony whereof I affix my signature 45 in presence of two witnesses.

WALTER L. CULVER.

Witnesses:

JOHN C. HIGDON,
JOHN D. RIPPEY.
